JOHN DALBY, OF PAWTUCKET, RHODE ISLAND.

BOBBIN-WINDING MACHINE.

1,343,768.

Specification of Letters Patent. Patented June 15, 1920.

Application filed February 15, 1919. Serial No. 277,200.

To all whom it may concern:

Be it known that I, JOHN DALBY, a subject of Great Britain, residing at Pawtucket, in the county of Providence and State of Rhode Island, have invented a new and useful Improvement in Bobbin-Winding Machines, of which the following is a specification.

My invention has reference to an improvement in bobbin winding machines and more particularly to an improvement in bobbin winding machines for winding bobbins for lace looms.

In the usual construction of bobbin winding machines for winding lace loom bobbins, the threads go around a felt covered tension drum and are then wound on the bobbins which are on a square removable shaft driven by a belt and pulley. The tension on the threads is controlled by a hand operated tension device on the tension drum. In the use of the hand tension controlled machines it has been found practically impossible to uniformly wind two sets of bobbins having the required tension, as no two operators, operating the tension by hand, are able to give the same tension to the threads wound on the bobbins. In practice it has been found that even the same operator will vary the tension from that required to give the best result in the loom. With the hand operated tension the threads are usually wound uneven in the bobbin, a greater tension may be given at the periphery when the greatest tension should be at the hub and gradually diminish to the periphery, or the threads may be wound too hard or overlap causing the thin sides of the bobbin to bulge out and when the bobbin is heated and com-

pressed to the required thinness, the threads will gum up and break. By increasing the tension of the threads at the hub where the thin sides are the strongest and gradually diminish the tension to the periphery where the sides are the weakest the length of thread wound on a bobbin may be increased ten or more per cent. If the sides of the bobbins are bulged by hard winding they will cause breaking of the beam threads in the loom.

The object of my invention is to improve the construction of a bobbin winding machine for winding lace loom bobbins, whereby the tension on the threads is governed automatically, and when the automatic tension device is set for a prede-

termined tension, the tension on the threads is thereafter controlled by the automatic tension device and the human element for this purpose eliminated.

A further object of my invention is to improve the construction of a bobbin winding machine for winding lace loom bobbins, whereby the automatic tension device will govern the tension so that the tension on the threads will be the greatest at the hub and gradually diminish to the periphery and that each set of 120 to 140 bobbins when wound, will all have the same required tension.

My invention consists in the peculiar and novel construction of a bobbin winding machine for winding lace loom bobbins, said machine having an automatic bobbin winding tension mechanism and details of construction, as will be more fully set forth hereinafter and claimed.

Figure 1 is a side view of a lace loom bobbin winding machine provided with my improved automatic bobbin tension controlling mechanism.

Fig. 2 is a diagrammatic figure illustrating the method of carrying the threads through the bobbin winding machine to the bobbins.

Fig. 3 is an enlarged side view partly in section, of the spring end of the automatic tension controlling mechanism.

Fig. 4 is an enlarged side view partly in section of the cam end of the automatic tension controlling mechanism.

Fig. 5 is a side view of a lace loom bobbin, and

Fig. 6 is an edge view of the lace loom bobbin.

In the drawings 7 indicates the bed of the machine at one end of which are uprights 8.8 only one of which is shown. Each 8 has a bearing for a shaft 9 to which is secured a felt covered transverse tension drum 10, a brake drum 11, and a worm gear 12, shown in broken lines in Fig. 1. Each upright 8 also has bearings 13.13 which rotatably support transverse rolls 14.14, an extension 15 which supports transverse rods 16.16 and a transverse reed 17 at each side of the rolls 14.14. A cam shaft 18 is rotatably supported in bearings 19 in a support on the bed 7. Secured to the cam shaft 18 is a worm 20, shown in broken lines in Fig. 1, 110 a pinion 21 and a cam 22 have a one turn helical cam groove 23, which begins near

the center and ends near the periphery of the cam, as shown in Fig. 4. A clutch, not shown, is interposed between the cam shaft 18 and the worm 20. A segmental gear 24 is pivotally secured to a bearing 25 on the bed 7, it meshes with the pinion 21 and has a handle 26 by which the cam 22 is reversed. A shaft 27 is rotatably supported at one end in a bearing 28 on the upright 8 and at the other end in a bearing 29, shown in broken lines, on the support which carries the bearing 19 on the bed 7. A worm 30, on the shaft 27 meshes with the worm gear 12 on the shaft 9 and a worm gear 31 on the shaft 27 meshes with the worm 20 on the cam shaft 18, thereby driving the cam shaft 18 from the shaft 9. The worm 30 and worm gear 31 are shown in broken lines in Fig. 1. The ratio of gearing between the shafts 9 and 18 is such that the cam 22 makes one revolution in one winding of the bobbins. A brake lever 32 is pivotally secured at its lower end to a bearing 33 on the bed 7 and has a shoe 34 in frictional engagement with the brake drum 11 and a hole 35 in its upper end. A rod 36 is constructed to have a shoulder 37 and a reduced end portion 38 which extends through the hole 35 in the brake lever 32. A collar 39 is slidably supported on the end portion 38 and a heavy coiled spring 40 on the portion 38 is in spring engagement with the collar 39 and the brake lever 32. A collar 41 is adjustably secured to the rod 36 by a bolt 42 and a light coiled spring 43 is in spring engagement with the collar 39 and with the movable collar 42, as shown in Fig. 3. A roll member 44 has a slot 45 for the cam shaft 18, a roll 46, which enters the cam groove 23, as shown in broken lines in Fig. 4, an end bore 47 into which the end 48 of the rod 36 extends and in which it is adjustably secured by a bolt 49. A bobbin shaft 50 having a pulley 51 and a square portion, is rotatably supported in bearings 52 on the bed 7. As shown in Fig. 5 the bobbin 53 has a square central hole 54 by which it is detachably secured to the bobbin shaft 50, the square portion of which is detachable. The cam 22, collar 39 and springs 40 and 43 are shown in the position they would assume at the beginning of winding the one hundred and twenty to one hundred and forty bobbins, which are wound at one time.

In the operation of my improved bobbin winding machine, the required tension is obtained on the threads 55, by adjusting the rod 36 in the bore 47 and the collar 41 on the rod 36. The threads 55 come from a jack, not shown, then between the rods 16, 16, through the first reed 17, over the first roll 14, then around the tension drum 10, then over the second roll 14, and through the second reed 17 to the bobbins 53.53 as

shown in Fig. 2, in which they are wound, by the pulley 51 on the bobbin shaft. At the beginning of the winding both of the springs 40 and 43 are compressed with the collar 39 against the shoulder 37 of the rod 36. The heavy spring 40 is now exerting its greatest tension or pressure on the lever 32 and brake shoe 34 thereby giving the greatest friction on the brake drum 11 and greatest tension on the threads 55.55 as they are wound on the bobbins. As the cam 22 turns in the direction of the arrow as shown in Fig. 4, the rod 36 moves toward the cam and the heavy spring 40 lengthening out, gradually reduces its pressure on the lever 32 until it reaches its limit of expansion when it blends with the light spring 43 which acting on the collar 39, which now leaves the shoulder 37, comes into action and through the lengthening of the light spring 43 gradually reduces the tension on the threads to the end of the winding. The full bobbins are then replaced by empty bobbins and the cam reversed by the segmental gear 24, thereby placing the springs 40 and 43 again under the required varying tension for winding the next set of bobbins.

By the use of my improved bobbin winding machine for winding the brass bobbins used in lace looms, each bobbin is wound under the same required varying tension, that is to say, the thread has the greatest tension at the hub which tension gradually diminishes to the periphery of the bobbin, and the threads in all of the different sets of bobbins, wound at different times, all have the same required tension, which has been proved to be impossible where the tension is manually controlled during the winding as heretofore. The thread may be increased in length in each bobbin ten or more per cent., a material reduction in threading is obtained, production increased and time and labor reduced.

It is evident that the tension springs could be multiplied on the rod and the means of setting the tension could be varied, within the scope of the appended claims.

Having thus described my invention I claim as new:—

1. In a machine for winding the bobbins of lace looms, a bed, a shaft rotatably supported on the bed, a tension drum secured to the shaft, a brake drum secured to the shaft, a brake lever pivotally secured to the bed and having a brake shoe frictionally engaging the brake drum, a cam shaft rotatably supported on the bed, a cam secured to the cam shaft, means operatively connecting the cam with the brake lever whereby the brake shoe exerts a gradually diminishing frictional resistance on the brake drum and means for reversing the cam.

2. In a machine for winding the bobbins of lace looms, a bed, a shaft rotatably sup-

- ported on the bed, a tension drum secured to the shaft, a brake drum secured to the shaft, a brake lever pivotally secured to the bed and having a brake shoe frictionally engaged 50 the brake drum, a cam shaft rotatably supported on the bed, a cam secured to the cam shaft, means operatively connecting the tension drum shaft with the cam shaft for rotating the cam, means operatively connecting 55 the cam with the brake lever whereby the brake shoe exerts a gradually diminishing frictional resistance on the brake drum and means for giving a retrograde movement to the cam.
- 10 3. In a machine for winding the bobbins of lace looms, a bed, a bobbin winding shaft rotatably supported on the bed, means for holding a plurality of lace loom bobbins on the shaft, means for revolving the shaft, a tension drum shaft rotatably supported on the bed, a tension drum and a brake drum secured to the shaft, a brake lever pivotally secured to the bed and having a brake shoe frictionally engaging the brake drum, a cam shaft rotatably supported on the bed, a cam secured to the cam shaft, means operatively connecting the tension drum shaft with the cam shaft for rotating the cam, means operatively connecting the cam with 25 the brake lever whereby the brake shoe exerts a gradually diminishing frictional resistance on the brake drum and means for giving a retrograde movement to the cam.
- 15 4. In a machine for winding the bobbins of lace looms, a bed, a tension drum shaft rotatably supported on the bed, a tension drum and a brake drum secured to the shaft, a brake lever pivotally secured to the bed and having a brake shoe frictionally engaging 30 the brake drum, a cam shaft rotatably supported on the bed, a cam having a helical cam groove on the cam shaft, a brake drum on the tension drum shaft of the machine, a brake lever having a brake shoe frictionally engaging the brake drum, means for rotating the cam shaft, means for giving a retrograde movement to the cam and 35 means operatively connecting the cam with the brake lever, whereby the brake shoe exerts a gradually diminishing frictional resistance on the brake drum.
- 20 5. An automatic tension controlling mechanism for lace loom bobbin winding machines comprising a cam having a helical groove, a brake drum on the shaft of the tension drum, a brake lever having a brake shoe frictionally engaging the brake drum, a member having a roll engaging with the cam groove in the cam, a rod having a shoulder and a reduced end extending through a hole in the brake lever, a loose collar on the reduced end, a heavy coiled spring intermediate the loose collar and the brake lever, a collar secured 40 to the rod, a light coiled spring intermediate the fast and loose collars, whereby the brake shoe exerts a gradually diminishing frictional resistance on the brake drum and means for giving a retrograde movement to the cam.
- 25 6. The combination with a lace loom bobbin winding machine of a cam shaft, a cam having a helical cam groove on the cam shaft, a brake drum on the tension drum shaft of the machine, a brake lever having a brake shoe frictionally engaging the brake drum, means for rotating the cam shaft, means for giving a retrograde movement to the cam and 45 means operatively connecting the cam with the brake lever, whereby the brake shoe exerts a gradually diminishing frictional resistance on the brake drum.

In testimony whereof, I have signed my name to this specification.

JOHN DALEY.
